UNITED STATES PATENT OFFICE

163,462

BICYCLE

Harry W. Kranz, Lakewood, Ohio, assignor to The
Cleveland Welding Company, Cleveland, Ohio,
a corporation of Ohio

Application April 29, 1950, Serial No. 9,588

Term of patent 7 years

(Cl. D90—5)

To all whom it may concern:

Be it known that I, Harry W. Kranz, a citizen of the United States, and resident of Lakewood, county of Cuyahoga, and State of Ohio, have invented a new, original, and ornamental Design for a Bicycle, of which the following is a specification, reference being had to the accompanying drawing forming part hereof.

Fig. 1 is a side elevational view of a bicycle, showing my new design; and

Fig. 2 is a transverse cross-sectional view thereof taken substantially along the lines 2—2 of Fig. 1.

The dominant features of my design reside in that portion shown in full lines of the drawing.

I claim:

The ornamental design for a bicycle, as shown and described.

HARRY W. KRANZ.
